UNITED STATES PATENT OFFICE.

FRANK T. HITES, OF ST. LOUIS, MISSOURI.

TOBACCO PIPE.

Application filed July 22, 1922. Serial No. 576,753.

To all whom it may concern:

Be it known that I, FRANK T. HITES, a citizen of the United States, residing at the city of St. Louis, Missouri, have invented 5 a new and useful Tobacco Pipe, of which the following is a specification.

This invention relates to tobacco pipes.

An object of the invention is to provide a pipe having a stem equipped with a device 10 of novel and improved construction to prevent the stem from becoming clogged.

Another object of the invention is to provide a tobacco pipe having a stem provided with a smoke passage opening into 15 the bowl of the pipes, and also provided with an inclined passage opening into the smoke passage and a groove at the outer end of the inclined passage, in combination with a slide for sealing the groove and the inclined passage therefrom, and a wire or rod 20 in connection with the slide extending through the inclined passage and movable by the slide to open the smoke passage into the bowl to prevent clogging of the smoke 25 passage.

In the drawings—

Fig. 1 is a plan view of my improved pipe with parts in normal position.

Fig. 2 is a plan view of the pipe showing 30 a rod or wire projected into the bowl of the pipe by the slide.

Fig. 3 is a sectional view of the pipe showing the construction and arrangement thereof.

35 The pipe includes the usual bowl 1 having a stem 2 in connection therewith provided with a smoke passage 3 opening into the bottom of the bowl.

An inclined passage or hole 4 is formed 40 in the stem 2 beginning at a point near the opening of the passage 3 into the bowl and extending obliquely upwardly and outwardly into a groove 5 in the upper side of the stem. The groove 5 has its bottom 45 wall inclined in continuation of the bottom wall of the inclined hole or passage 4. The outer end of the groove 5 forms an abrupt shoulder 6.

A rod or wire 7 is mounted in the groove 5 and in the hole or passage 4 and, in normal position of parts, has its inner end above the smoke passage 3. The rod or wire 7 rests upon the bottom wall of the groove 5 and on its outer end is formed with an upward extension 8 which engages in a hole 55 in a knob 9 on the outer end of a slide 10.

Preferably the extension 8 is slidable in the hole in the knob 9 to permit proper relative movement of the parts when the slide 10 is moved toward the bowl of the pipe and 60 then to its closed position as shown in Figs. 1 and 3, without straining the rod or the slide.

The slide is held within a guide comprising a pair of bands 11 encircling and rigidly secured to the pipe stem and integrally united by a plate portion 12. The outer band 11 is formed with an extension 13 upon which the outer end of the slide rests when the slide is in its outer or closed 70 position.

A slot 14 is formed through the plate 12 and through portions of the bands 11 registering with the groove 5 to accommodate the extension 8 of the wire or rod 7. The slide 75 10 operates under turned-over extensions 15 in connection with the inner band 11 and under turned-over portions 16 in connection with the plate 12 between the bands 11. The slide is of such length that when the inner 80 end is against the bowl of the pipe the outer end is held by the guide member 15, inward movement of the slide being stopped by contact with the pipe bowl while outward movement of the slide is stopped by contact of the extension 8 with the end wall of the groove 5.

The extent of movement of the slide and of the wire or rod 7 is sufficient to cause the inner end of the wire or rod to enter the 90 bowl of the pipe when the slide is pushed inwardly; and when the slide is moved outwardly the wire or rod 7 is entirely within the bowl or passage 4 and does not in any way obstruct the smoke passage 3 through 95 the pipe stem. The slide and the wire or rod 7 cooperate to form a seal for the opening from the pipe passage so that there will be no interference with the proper functioning of the pipe when in use.

100 The specific construction and arrangement may be varied without departure from the nature and principle of the invention.

I do not restrict myself unessentially, but what I claim and desire to secure by Letters 105 Patent is:—

1. In a tobacco pipe, a bowl, a stem in connection with the bowl having a smoke passage opening therethrough from the bowl and having an inclined passage from the 110 smoke passage toward one side of the stem, and a groove in said side of the stem into

which the inclined passage opens, a band encircling the stem and being rigid therewith and having a slot therethrough opening into said groove, a longitudinally movable slide for closing said groove, means in connection with said band preventing said slide from turning around the stem and guiding said slide in its longitudinal movements, and a wire in connection with said slide extending through said inclined passage.

2. A tobacco pipe comprising a bowl, a stem in connection with the bowl having a smoke passage and an inclined passage opening into the smoke passage adjacent to the bowl, a slide movable longitudinally on the stem for closing the inclined passage, a device supported by the stem preventing said slide from turning around the stem and

guiding the slide in its longitudinal movements, and a wire mounted in said inclined passage and having its outer end engaging said slide.

3. A tobacco pipe comprising a bowl, a stem in connection with the bowl having a smoke passage and an inclined passage opening into the smoke passage adjacent to the bowl, a slide movable longitudinally on the stem for closing the inclined passage, a device supported by the stem preventing said slide from turning around the stem and guiding the slide in its longitudinal movements, a knob in connection with said slide having a hole in its inner side, and a wire mounted in said inclined passage having an outwardly bent portion at its outer end engaging in said hole.

FRANK T. HITES.
